(57) **CLAIM**

The ornamental design for a spacecraft, as shown and described.

DESCRIPTION

FIG. 1 is a front overhead perspective view of a spacecraft according to an embodiment of the present invention;

FIG. 2 is a rear overhead perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof;

FIG. 8 is a bottom plan view thereof;

FIG. 9 is a front underside perspective view of the spacecraft in an alternate embodiment;

FIG. 10 is a front elevation view of the spacecraft in its alternate embodiment;

FIG. 11 is a rear elevation view of the spacecraft in its alternate embodiment;

FIG. 12 is a right side elevation view of the spacecraft in its alternate embodiment;

FIG. 13 is a left side elevation view of the spacecraft in its alternate embodiment;

FIG. 14 is a top plan view of the spacecraft in its alternate embodiment; and,

FIG. 15 is a bottom plan view of the spacecraft in its alternate embodiment.
